UNITED STATES PATENT OFFICE.

GEORGE F. TRIPP, OF FLINT, MICHIGAN.

REFRIGERATOR.

1,265,552.

Specification of Letters Patent. Patented May 7, 1918.

Application filed June 23, 1916. Serial No. 105,435.

To all whom it may concern:

Be it known that I, GEORGE F. TRIPP, a citizen of the United States, residing at Flint, in the county of Genesee and State of Michigan, have invented certain new and useful Improvements in Refrigerators; and I do hereby declare the following to be a full, clear, and exact description of the invention, such as will enable others skilled in the art to which it appertains to make and use the same.

The invention relates to a refrigerator.

The object of the present invention is to improve the construction of refrigerators and to provide a refrigerator of simple, practical and comparatively inexpensive construction adapted to be maintained in a cool sanitary condition without the use of ice and adapted also to have the atmosphere readily changed when desired so that the refrigerator will contain fresh, dry, cool, air.

A further object of the invention is to provide a refrigerator of this character equipped with means for maintaining a constant circulation of cool air throughout the refrigerator so as to produce a uniformly cool temperature in all portions of the refrigerator.

With these and other objects in view, the invention consists in the construction and novel combination of parts hereinafter fully described, illustrated in the accompanying drawing, and pointed out in the claims here-to appended; it being understood that various changes in the form, proportion, size and minor details of construction, within the scope of the claims, may be resorted to without departing from the spirit or sacrificing any of the advantages of the invention.

In the drawing

Figure 1 is a vertical sectional view of a refrigerator constructed in accordance with this invention,

Fig. 2 is a central vertical sectional view of the same taken at right angles to Fig. 1,

Figs. 3 and 4 are detail views on an enlarged scale illustrating the construction of the ventilator tubes,

Fig. 5 is a detail sectional view on the line 5—5 of Fig. 1.

Like numerals of reference designate corresponding parts in the several figures of the drawing.

In the accompanying drawing in which is illustrated the preferred embodiment of

the invention, 1 designates a refrigerator designed to be mounted in a house and located in the kitchen or other portion of the same upon the first floor 2 and provided with horizontal shelves 3 arranged at intervals and provided with openings 4 to permit the air to circulate through them from the bottom to the top of the refrigerator. The refrigerator is also provided adjacent to the top with a horizontal partition 5 terminating short of the side walls of the refrigerator to provide side openings 6 and extending downwardly from the top portion of the refrigerator is a vertical warm air pipe 7 connected at its upper end to the horizontal partition 5 and an opening 8 thereof. The warm air pipe 7 extends downwardly through the bottom 9 of the refrigerator and through the basement or cellar under the house into the ground, about ten to thirty feet so that the ground will be sufficiently cold during all seasons of the year to cool the air passing through the vertical pipe 7. The warm air pipe extends into an outer pipe 11 of greater diameter than the pipe 7 to provide a surrounding space 12 for the upward passage of the air from the lower end of the warm air pipe. The outer pipe 11 is provided at its lower end with a cap 13 or other suitable closure and the upper end of the said pipe 11 extends through the bottom of the refrigerator and projects above the same and terminates beneath an annular hood 15 which forms both a shield 90 and a deflector for directing the cold air outwardly. The hood also prevents anything within the refrigerator from dropping down the outer pipe and interfering with the circulation of air through the same. 95 The hood 15 is provided with a raised central portion 16 which is suitably secured to the warm air pipe above the upper end of the outer pipe 11. The inner warm air pipe is supported within the outer pipe at spaced 100 points by spiders 17 which maintain the inner warm air pipe in proper spaced relation within the outer pipe. While the inner and outer pipes are shown continuous in the accompanying drawing they may of 105 course in practice be made up of any desired number of sections to facilitate the installation of the warm and cold air pipes as will be readily understood. The exposed portion of the outer pipe at the basement 110 or cellar 10 is provided with an outer covering 18 of asbestos or other suitable ma-

terial which is a non-conductor of heat to prevent the temperature of the basement or cellar from affecting the air passing through the outer cold air pipe. The air from the 5 top of the refrigerator is circulated positively through the inner warm air tube by means of a fan 19 arranged within a suitable casing 20 and connected with an electric motor 21 preferably mounted upon the top of 10 the refrigerator and having its shaft 22 extending through the top of the refrigerator.

The fan casing is provided at the top with an inlet opening or eye 23 and it has a bottom opening 24 which registers with the 15 opening in the horizontal partition upon which the fan casing is mounted.

The refrigerator is provided in its top with ventilating openings 25 from which extend approximately L-shaped ventilator 20 tubes 26 having pivoted dampers 27 adapted to control the inlet of air into the refrigerator so that the desired amount of pure fresh air may be admitted to the refrigerator. The electric motor may be of any desired 25 construction and will be supplied with current from any ordinary fixture and when the fan is operated the warm air from the top of the refrigerator will be driven through the inner warm air pipe and ex- 30 pelled from the lower end thereof and caused to rise or pass upwardly through the cold air pipe where it will be chilled and introduced into the refrigerator at the bottom thereof. The cold air from the upper end 35 of the outer pipe will pass upwardly through the openings in the horizontal shelves and will be drawn in by the fan and a continuous circulation of cool air through the refrigerator will be maintained while 40 the fan is in operation. Also the ventilating devices will enable the atmosphere within the refrigerator to be changed as required or desired. The upper horizontal partition 5 is arranged in spaced relation 45 with the top of the refrigerator to form an air chamber 28 and the openings 6 at opposite sides of the chamber will permit the air to enter the said chamber from both sides of the refrigerator, but openings may be pro-

vided at any other desired points as will be 50 readily understood. The warm air pipe is preferably provided within the refrigerator with upper and lower elbows 29 and 30 to arrange the intermediate portion of the 55 warm air pipe at the back of the refrigerator so as not to interfere with the filling of the shelves with the articles to be cooled.

What is claimed is:—

1. The combination with a refrigerator provided at the top with an air chamber 60 communicating with the interior of the refrigerator, of a cold air pipe communicating at its upper end with the refrigerator at the bottom thereof and extending downwardly therefrom and being of sufficient length to 65 extend into the ground so as to be chilled thereby, and a warm air pipe connected at its upper end with a casing, a fan within the casing, said pipe extending downwardly through the refrigerator into the cold air 70 pipe and arranged to discharge air into the cold air pipe at the bottom thereof.

2. The combination with a refrigerator provided at the top with an air chamber 75 communicating with the interior of the refrigerator, of a cold air pipe communicating at its upper end with the refrigerator at the bottom thereof and extending downwardly therefrom and being of sufficient length to extend into the ground so as to be 80 chilled thereby, a warm air pipe connected at its upper end with a casing, a fan within the casing, said pipe extending downwardly through the refrigerator into the cold air pipe and arranged to discharge air into the 85 cold air pipe at the bottom thereof, said cold air pipe projecting above the bottom of the refrigerator, and a hood mounted on the warm air pipe and extending over the upper 90 end of the cold air pipe in spaced relation with the same and projecting below the upper edge thereof.

In testimony whereof I affix my signature in the presence of two witnesses.

GEORGE F. TRIPP.
